UNITED STATES PATENT OFFICE.

EUGENE ANSELME LAHIERE, OF WASHINGTON, DISTRICT OF COLUMBIA.

DESIGN FOR A TOY.

46,256.

Specification for Design.

Patented Aug. 11, 1914.

Application filed January 23, 1914. Serial No. 814,012. Term of patent 7 years.

To all whom it may concern:

Be it known that I, EUGENE A. LAHIERE, a citizen of France, residing at Washington, in the District of Columbia, have invented a new, original, and ornamental Design for a Toy, of which the following is a specification, reference being had to the accompanying drawing, forming part hereof.

The drawing is a perspective view of a toy, showing my new design.

I claim:

The ornamental design for a toy, as shown.

EUGENE ANSELME LAHIERE. [L. S.]
